UNITED STATES PATENT OFFICE

2,142,253

ELECTRICAL CIRCUIT

Thomas J. Nunan, Summit, N. J., assignor to The
Clark Thread Company, Newark, N. J., a cor-
poration of New Jersey

Application March 4, 1937, Serial No. 128,996

3 Claims.

(Cl. 73—51)

This invention relates to a novel and improved form of electrical circuit, more particularly a circuit which may be automatically operated to record a plurality of operations. For the purpose of illustration, this circuit is illustrated and will be described in connection with a device for testing thread, as more fully described and claimed in my copending application Ser. No. 9,428, filed March 5, 1935. The present application is a continuation in part of divisible subject matter contained in said copending application.

In the accompanying drawings, I have shown selected embodiments of the invention, and in those drawings:

Fig. 1 is a vertical face view of an apparatus with which the invention may be employed;

Fig. 2 is a sectional view on a slightly enlarged scale and taken substantially on the line 2—2 of Fig. 1;

Fig. 3 is a view showing an elevation of the scale appearing in Fig. 1 as viewed from the right, parts being broken away and other parts shown in section, better to illustrate the operation of the apparatus;

Fig. 4A and Fig. 4B together form a wiring diagram, illustrating a selected embodiment of the circuit claimed herein;

Fig. 5 is a wiring diagram of another circuit which may be used instead of the circuit of Figs. 4A and 4B to perform the same general functions and also certain other functions;

Fig. 6 is a view on an enlarged scale showing a detail of the circuit of Fig. 5;

Figs. 7 and 8 are views taken at right angles to each other and showing the construction of one of the rotary switches appearing in the various wiring diagrams;

Figs. 9 and 10 are views illustrating the operation of certain switches appearing in Fig. 5;

Fig. 11 is a view illustrating the operation of another switch appearing in Fig. 5;

Fig. 12 is a fragmentary view taken in a plane parallel to the plane of Fig. 1 but on the reverse side of the panel and showing the relation of certain parts;

Fig. 13 is a wiring diagram illustrating the operation of a modified embodiment of the invention;

Figs. 14 and 15 are diagrammatic views illustrating the operation of the embodiment of Fig. 13.

For the purpose of convenience, the invention is illustrated as embodied in an apparatus for testing thread and for measuring the breaking

strength of the thread tested. This apparatus may comprise a thread cylinder 1 forming a source of supply for thread to be tested and from which the thread 2 passes through a tension device 3 of any suitable construction and is then carried by a rotary frame 4 to a clamp 5 supported upon a bracket 6 secured to a movable part 7 of a scale 8. The scale is selected as a suitable form of indicator or measuring instrument and may be of any of the well-known forms which may be found suitable for the purpose. Therefore the details of the scale mechanism will not be described except as they are of interest in understanding the invention. The indicating part of the measuring instrument may be omitted entirely for some purposes, and therefore the word "indicator" is used merely for convenience of expression.

For the purpose of convenience, I shall refer to the clamp 5 as the indicator clamp, since it moves with the indicator.

The frame 4 is rotatably mounted about its axis 9 on a suitable support 10, here shown in the form of a panel extending upwardly from a base 11, and is operated in a clockwise direction, as viewed in Fig. 1. The operating means will be more fully described presently.

Rotatably mounted upon the panel 10 is a rock shaft 12 having on the front of the panel a lever 13 secured thereto, and upon the outer end of this lever is a clamp 14 which, for the sake of convenience, I shall refer to as the breaking clamp. On the back of the panel 10 the rock shaft 12 has an arm 15 which is urged towards the base 11 by means of a spring 16.

By means to be described later, the clamps 5 and 14 are periodically operated in synchronism with the movement of the lever 13 and the frame 4. The frame 4, as indicated, comprises a plurality of arms, here shown as four in number and which I have designated as 17, 18, 19, and 20, and is given an intermittent rotation in the direction indicated by the arrow in Fig. 1.

On the end of each of the arms 17, 18, 19, and 20 is a feed clamp formed of two jaws 21 and 22 which are spring-pressed towards each other with sufficient force to yieldingly clamp the thread therebetween as the thread is pulled from the source of supply 1. At appropriate times in the operation of the frame, the jaws 21 may be forced apart by release members 23 and 24.

The frame is given an intermittent motion by any suitable means which may comprise a Geneva movement of which the driving member 55

is operated by a cam shaft 35. This shaft in turn is continually rotated from a motor 37 (Fig. 12) through a gearing train contained in a gear box 38 which rotates a pinion 39 meshing with a gear 40 on the shaft 35. On the shaft 35 in front of the panel 10 is a cam 41 adapted to engage a roller 42 on the lever 13.

As more fully described and claimed in said copending application, the thread is brought in successive lengths into engagement with the clamps 5 and 14, and the cam 41 then depresses the lever 13 with its clamp 16 until the thread is broken. The release members 23 and 24 operate at proper times to release the hold of the feed clamps on the thread or pieces of thread held thereby. The details of such operation, however, are not necessary to an understanding of the invention claimed herein.

The two clamps 5 and 14 are controlled in their operation by solenoids 63 which are energized at the proper time to clamp the thread, and then de-energized at the proper time to release the thread held by the clamps.

As the cam 41 depresses the clamp 14, tension is exerted on the thread between the clamps 5 and 14 and thus causes depression of the bracket 6 to actuate the scale or other indicator and to cause the pointer 66 on the scale to move along the scale face 66'. Attached to the pointer is a pawl 67 cooperating with the ratchet 68 pivotally mounted on the scale frame at 69. The ratchet has as many teeth thereon as there are units on the scale face 66', so that the pointer will not return to zero until the pawl and ratchet are released from engagement, but will remain in position where they will indicate the nearest unit of force required to break the thread between the clamps 5 and 14.

The ratchet and pawl may be released at the proper time by the energizing of a solenoid 70 pulling upon a rod 71 fastened to the ratchet, this pull being against the action of a spring 72 which tends to hold the ratchet in its uppermost position to contact with the pawl 67.

The operation of many of the different elements is controlled by electrical circuits, and these circuits in turn may be controlled by means of a light sensitive element, such as a photo-electric cell of known construction, which is shown at 73. The cell may be acted upon by a lamp indicated at 74, and light from which passes through a lens 75 which is directed towards the cell 73.

Between the lamp and the cell is disposed a shutter 76 of arcuate form concentric with the center of movement of the pointer 66 and having therein a plurality of holes 77 likewise arranged on an arc concentric with the center of movement of the pointer. The shutter, lamp, and cell are so arranged that, as the pointer moves, the shutter will pass between the lamp and cell so that the lamp may act upon the cell through the holes as they pass successively between the lamp and cell. The result will be a series of electrical impulses, as is well known to those skilled in the art, and by making the holes correspond in number to the units of force indicated by the indicator, or by having those holes occupy a certain predetermined relation to such units of force, the impulses may be used as a measure of that force. In this illustrated embodiment, it will be assumed that when the pointer 66 is at zero position, the lamp and cell will be opposite an opaque portion of the shutter spaced from the first hole a distance equal to the hole spacing.

The action of the light upon the cell will cause

a variation in the resistance of an electrical circuit, as is well known in the electrical art, and these variations or impulses are employed to operate a recorder, here shown in the form of a calculating machine 78. This calculating machine 5 may take any desired form, but for the sake of illustration, I have shown a machine sold under the name of the "Underwood Sundstrand". This type of machine is convenient, since it has a small number of keys on the keyboard, although the 10 invention is not limited to the use of that particular machine.

The recorder or calculator machine is one which preferably has a keyboard with a plurality of keys, and the particular recorder selected for 15 illustration has nine keys. These keys are adapted to print the numerals 1 to 9, inclusive, in a manner well known in the art, and the machine is also one in which the depressing of a key prints a record, for example, a numeral, upon a record 20 strip of paper 83. A further detailed description of the recorder is deemed unnecessary.

Each finger is adapted to be operated by a solenoid 92, and these solenoids have been designated in Fig. 4—B by the numeral 92 followed by 25 a number or character indicating the key or other part of the recorder which it is adapted to operate. For convenience of arrangement of the circuits, two additional solenoids are provided for the keys numbered 1 and 2, these additional solenoids being designated 92—1a and 92—2a. These additional solenoids are provided because this particular machine has only ten keys for the recording of digits and certain recording figures may require two actuations of the keys numbered 30 1 and 2. By the above described arrangement it is possible to have double actuation of the keys numbered 1 and 2 so as to give any quantity up to 32.

Referring now more particularly to Figs. 4—A 40 and 4—B, I shall describe the electrical circuits shown therein and which are arranged to control the operation of the mechanism previously described. These circuits include certain switches shown in the other figures previously described. 45 Two of such switches are indicated in Fig. 2 as mercury switches 95 and 96, each operated by a cam 97 and 98, respectively, on the cam shaft 35. The switch 95 is used to control the solenoids 63 operating the indicator clamp 5 and the breaking 50 clamp 14, these two clamps operating in unison, and the switch 96 is used to control the solenoid 70 for depressing the ratchet 68. The switch 95 is normally open and the switch 96 is normally closed.

In Fig. 3 is shown another switch 99, which is a cut-off switch controlled by the movement of the beam 100 of the scale. When the downward movement of the bracket 6 causes movement of the element 7, the right-hand end of the beam in 60 Fig. 3 is raised, permitting the switch 99 to close, but when the scale is not being operated, this switch is open. The shutter 76 has an opaque portion disposed between the lamp and the cell when the scale is inoperative, that is to say, when the pointer is at zero position, and the contacts of the switch 99 are so designed that they will come into engagement with each other and close the switch by the time that the shutter has moved a sufficient amount so that the light from the 70 lamp will pass through the first one of the holes 77 corresponding to the first ounce.

Upon return movement of the scale beam to initial position, it will open the switch 99, the pointer and shutter being retained, however, by 75

the pawl and ratchet until operation of the solenoid 70, the scale construction readily permitting this action. In this way I insure against passage of light through the holes in the shutter on its 5 return movement.

Most of the circuits appearing in Fig. 4—A are disposed upon the scale or beneath the cover 101 shown in Fig. 2, whereas most of the circuits appearing in Fig. 4—B will be disposed in a cabinet 102 shown in Fig. 1. On the face of this cabinet 10 may be conveniently arranged means to operate certain switches, such as the "breaker" switch 103, the "recorder" switch 104, and the "reset" switch 105.

One of the features of my invention is the provision of means for automatically operating the device so that any required number of breaks may take place, and then the operation of the device will automatically cease. For example, if it is 20 desired to test a thread by breaking it twenty-five times, the device may be automatically set so that twenty-five lengths of thread will be brought into engagement with the two clamps 5 and 14 and broken, the force required to cause each break 25 recorded, and the number of operations and total force recorded. The total force may then be readily divided by the number of breaks to obtain the average strength determined by the run of tests.

In order to control this operation of the device, I provide a "breaks required" switch 106, which may include a pointer, as shown in Fig. 1, adapted to move over a numbered face, and connected to a contact 107 (Fig. 4—B). I find it convenient 30 to have the face numbered so that by moving the pointer from one number to another, the number of breaks may be varied by five. For example, in Fig. 1, the pointer is shown as resting upon the numeral 5, which means that when the device is 35 operated with the pointer so set, the thread will be broken twenty-five times during the run of the tests.

In Fig. 4—B, I have shown conventionally the thirteen solenoids 92—1, etc., adapted to operate 40 the various fingers which in turn actuate the keys of the recorder. In order to avoid confusion, I have omitted these elements operated by the solenoids, except diagrammatically, in one instance.

Electric current may be supplied to the device 45 from any suitable source, here indicated in Fig. 4—B as two line conductors 108 and 109 carrying a 110 volt, 60 cycle, alternating current. The conductors 108 and 109 lead to the opposite sides of the motor 37, the conductor 108 having there- 50 in a switch 110 operated by a solenoid 111, the switch and solenoid together forming what for convenience may be referred to as the "trip relay." The function of this trip relay will be more fully discussed later.

The solenoids 63 are connected by conductors 55 112 and 113 to the conductors 108 and 109, respectively, and lead through the primary of a transformer 114, the secondary of which is connected through a rectifier 115 with the solenoids 63, these solenoids being arranged in parallel with each other through variable resistances, if such are desired. The purpose of the rectifier is to provide a one-way current through the solenoids, as will be apparent to those skilled in the art.

In the conductor 112 is shown the cam-operated switch 95, which switch thus controls the 60 operation of the solenoids, and it will be seen that this operation is also controlled by means of the "breaker switch" 103 shown as located in the conductor 109.

The lamp 74 is likewise connected, by means of the conductors 116 and 117, to the conductors 108 and 109 and lead therefrom to the primary of a transformer 118, the secondary of which is connected to the lamp 74 by the conductors 119 and 120. It will be seen that the cut-off switch 99, shown located on the scale in Fig. 3, is indicated in the conductor 119, and therefore this switch controls the operation of the lamp.

Likewise connected to the conductors 108 and 109 is the photo-electric cell 73. This connection may be made by the conductor 121 connected to the conductor 116 and thus to the conductor 108, the conductor 121 leading to the amplifier 122. This amplifier is of known construction, and one form which I have found suitable for the present purpose is sold under the name of "Westinghouse Type LE Amplifier." The other line conductor 108 may be connected to the other side of the amplifier 122 by means 20 of the conductor 123. From the amplifier 122 lead two input leads 124 and 125 to opposite sides of the cell 73. The "recorder switch" 104 is shown as being located in the conductor 123 and thus this switch controls the amplifier and through the 25 amplifier controls the operation of the photo-electric cell, as well as of other elements to be described later.

The ratchet solenoid 70 may be connected 30 through the conductor 116 connected to one of the line conductors 108, part of the conductor 121, conductor 126, switch 127, conductor 128, rectifier 129, conductor 130, to one side of the solenoid. The other side of the solenoid 70 may be connected to the line conductor 109 through the 35 conductor 131, rectifier 129, switch 104, and conductor 123. It will be noted that the switch 96 is located in the conductor 131.

It will thus be seen that the ratchet solenoid, photo-electric cell, lamp, motor, and clamp 40 solenoids are all connected across the line formed by the conductors 108 and 109.

By the conductors 116, 121, 126, 128, 123, and switch 104, the rectifier 129 is likewise connected across the same line. This rectifier has the function, known in the art, of giving the effect of a one-way current, and in the arrangement illustrated it is used to supply current to substantially all the recording apparatus.

Current through the rectifier, and consequently 50 through the recording apparatus, is controlled by the "recorder switch" 104 and also by the switch 121, which in turn is controlled by the solenoid 132, this switch and solenoid forming the dash-pot relay or other time-delay relay.

The various relay switches and magnet-operated switches indicated are supplied with the usual springs tending to keep them open or closed, as the case may be.

Connected to the amplifier 122 and receiving an 60 amplified current therefrom is a circuit including the conductors 133 and 134 connected to opposite sides of the magnet 135 controlling switches 136 and 137, this magnet and the switches together being constructed so as to be a quick-acting 65 relay.

The switch 136 is in a circuit leading from one side of the rectifier 129 through the conductors 138 and 139 to one side of the switch, the conductor 140 leading from the switch to the magnet 70 141 forming part of a rotary switch 142, and the conductors 143 and 144 leading to the other side of the rectifier 129.

The rotary switch 142 will hereinafter be referred to for convenience as rotary switch No. 1. 75

This switch and other rotary switches hereinafter referred to may be of the type shown in Figs. 7 and 8, and the construction of which will be more fully described later.

5 For the present it is sufficient to say that the switch 142 comprises a rotary shaft 145 upon which are secured the three wiping contacts or brushes 146, 147, and 148. In the diagram of Fig. 4—B, these three contacts are shown on separate centers but are connected together by dotted lines, to show that the centers are preferably coincident in practice. The wiping contact 146 wipes over homing contacts 149, while the wiping contacts 147 and 148 wipe over selector contacts 150 and 151, respectively.

The circuit closed by engagement of the wiping contact 146 with one of the contacts 149 includes the switch 152 operated by the magnet 141, the contacts 146 and 149, the conductor 153, the normally-closed switch 154, conductors 155, 156, and 158, leading to one side of the rectifier, while the other side of the rectifier is connected through the conductors 144 and 143 and magnet 141 to the switch 152.

25 The circuits closed by engagement of the wiping contacts 147 and 148 with the contacts 150 and 151, respectively, will be described later, as these circuits include apparatus which has not yet been described.

30 There is shown a plurality of relays referred to, respectively, as slow release relay No. 1, slow release relay No. 2, vibrating reed relay, slow release relay No. 3, and slow release relay No. 4. The circuits for these relays will now be described.

35 The magnet 157' operating the normally-open switch 157 of slow release No. 1, has current supplied to it on one side thereof by a conductor 153 leading through the switch 157 and the conductors 159 and 158 to one side of the rectifier 129, to the other side of which the magnet 156 is connected by means of conductors 144 and 143.

One side of the normally-open switch 157 is connected to one side of the rectifier 129 by means of the conductors 144, 143, and 159, while the other side of the switch 157 is connected to the other side of the rectifier by means of the conductor 160, magnet 161 of slow release relay No. 2, and conductors 162 and 138.

Slow release relay No. 2 comprises three switches, 163, 164, and 165. Of these three switches, 163 is normally closed and 164 is normally open, while 165 is normally in the position shown, closing one of two circuits, both of which will be more fully described later.

55 The magnet 166 of the vibrating reed relay has current supplied to one side thereof from one side of the rectifier 129 through the conductors 144, 143, 167, switch 164, and conductor 168, whereas the other side of the magnet is connected to the other side of the rectifier by means of the conductors 138, 156, and 169. The switch 170 of this relay is in the form of a reed which vibrates between two contacts, as plainly indicated.

The magnet 171 of slow release relay No. 3 and which operates the switches 154 and 197, has one side thereof connected to one side of the rectifier 129 by means of the conductor 172, switch 170, conductors 173, 143, and 146, whereas the other side of the magnet 171 is connected 70 to the same rectifier by the conductors 174, 156, and 138.

The magnet 175 of slow release relay No. 4 has one side thereof connected to one side of the rectifier 129 by means of the conductor 176, switch 75 165, conductors 177, 162, and 138, whereas the

other side of the magnet 175 is connected to the other side of the same rectifier by the conductor 178, switch 179, contacts 181 and 182, and conductors 183, 143, and 164.

The switch 179 is controlled by the magnet 180 and forms therewith part of rotary switch No. 2, which is generally similar to rotary switch No. 1, having not only the wiping contact 181 adapted to engage the homing contacts 182, but also having the wiping contact 184 mounted upon the same shaft 185 as is the contact 181, and adapted to engage any one of the energizing contacts 186.

Similarly, the switch identified as rotary switch No. 3 has two wiping contacts 187 and 188 mounted upon a common shaft 189, contact 187 being adapted to engage any one of the homing contacts 190 and contact 188 being adapted to engage any one of the trip contacts 191.

The magnet 180 of rotary switch No. 2 receives its current from the rectifier 129 through the conductors 138, 162, 177, switch 165, and conductor 192 (or conductor 176 and switch 175') and conductor 193 leading to one side of the magnet, the other side being connected by the conductors 194, 183, 143, and 144 to the other side of the rectifier 129.

Current may be supplied from the rectifier 129 through conductors 144, 143, and 183 and contact 184 to any one of the electric contacts 186 and thence through one of the solenoids 92 and one of the contacts 150 and 147, or 151 and 148, as the case may be, to the conductor 195 and thence through the switch 163, conductor 196, switch 197, conductors 198, 156, and 138 back to the other side of the rectifier 129.

35 The magnet 199 of rotary switch No. 3 has one side thereof supplied with current from one side of the rectifier 129 through conductors 138, 156, and 201, whereas the other side of the magnet 199 is connected by the conductor 200 to the contact 186—M and thence through the contact 184, and conductors 183, 143, and 144 to the other side of the rectifier 129.

It should be noted that the solenoid 92—M is not connected to rotary switch No. 1, like the other solenoids 92, but is in a circuit comprising conductors 144, 143, 183, contacts 184 and 186—M, and conductors 202, 162, and 138.

Rotary switch No. 3, like the other rotary switches, has associated with its magnet 199 a switch 203 controlled by that magnet and permitting current to pass from one side of the switch through conductor 203', magnet 199, conductor 204, and conductors 156 and 138, to one side of the rectifier, whereas current from the other side of the switch 203 may pass through the contact 187, one of the homing contacts 190, the switch 165, and conductors 204, 143, and 144, to the other side of the rectifier 129.

Current from the line conductor 108 may pass 60 through the conductor 205 to the conductor 188 and thence through one of the trip contacts 191, through one of the conductors 206 to one of the contacts 207 adapted to be engaged by the contact on the pointer 107 of the hand-operated switch 106 and thence through a conductor 208 65 and through the trip relay 111 to the other line conductor 109.

In operation, the thread is brought into position to be engaged by the two clamps 5 and 14 and is held by the feed clamp on the end of the arm 17 70 as in Fig. 1, being loosely engaged with the feed clamps on the arms 18 and 19 as previously described.

The pointer on the switch 106 which normally 75

occupies the zero position shown in dotted lines in Fig. 4-B, is now set at the point desired. In the illustrated embodiment, I have assumed that it is desired to break the thread twenty-five times, 5 and therefore I have set the pointer at 5 as indicated in Fig. 1 and in full lines in Fig. 4-B.

Normally, when idle the cam-operated switch 95 will be open and the switch 96 will be closed. However, as seen from Fig. 12, as soon as any substantial 10 rotation of the cam shaft 35 takes place in the direction of the arrow appearing in that figure, the switch 95 will be closed so as to operate the solenoids 63 and cause the jaws of the clamps 5 and 14 to operate to grip the thread. At the 15 same time, the switch 96 will be opened and remain open until near the end of the operation.

The cut-off switch 99 likewise will be open at the beginning of the operation so that the lamp 74 will not be lighted, but a relatively slight movement 20 of the beam 100 of the scale will cause the switch 99 to close.

The breaker switch 103 may now be closed, thus completing the circuits through the motor 37, through the solenoids 63, and also through the 25 lamp 74, except for the switches 95 and 99, which will be closed as soon as the motor has caused a small movement of the cam shaft 35.

The recorder switch 104 may be closed simultaneously with the switch 103, which will complete 30 the circuit through the amplifier 122 to the photo-electric cell 73. Closing of this switch 104 will likewise energize the solenoid 132 of the dash-pot relay to close the switch 127 in the circuit of the rectifier 129, but the dash-pot will 35 delay closing of the switch 127 for a sufficient time to permit the tubes of the amplifier 122 to become sufficiently warm to function, although the dash-pot relay may be omitted, if desired. As soon as the switch 127 does close, however, 40 current will be available for the automatic operation of all of the apparatus and circuits described above.

With the closing of the switch 103, the motor 37 will start operation, and one of the first results will be the closing of the switch 95 by rotation 45 of the cam shaft 35, to cause the solenoids 63 to operate the clamps 5 and 14 to grip the thread. The switch 96 will be opened by this same movement, as noted above. Another result 50 of the rotation of the cam shaft 35 is to operate the cam 41 and depress the lever 13, thus causing the thread to break between the clamps 5 and 14. As previously described, this action will cause an actuation of the indicator and a 55 consequent movement of the shutter 76 between the cell 73 and lamp 74.

The passage of each hole 77 in the shutter 76 will cause an impulse to be sent through the conductors 133 and 134 to the magnet 135 of the quick-acting relay of which that magnet forms a part, closing both of the switches 136 and 137. Closing of the switch 136 energizes the magnet 141 of rotary switch No. 1, and thereby causes the wiping contacts 146, 147, and 148 to move 60 one step or into engagement with the next one of the contacts 149, 150, and 151, respectively, after which the switches 136 and 137 will be opened by the action of the relay. The operation of a rotary switch one step for each impulse is 65 an action well known in the electrical art, but will be more fully described later in connection with the description of Figs. 7 and 8.

Since the holes 77 in the shutter are spaced apart a distance corresponding to units of weight, here taken as ounces, it will be seen that for 70

each ounce of force applied and indicated on the scale, one hole will pass the light and thus one impulse will be given to the movement of the rotary switch.

The quick-acting relay is constructed with the usual spring, which will cause the switch 136 to open immediately after one hole has passed the light, it being understood that with the passage of a hole, the resistance of the cell will change enough to affect the amount of current passing 10 through the relay sufficiently to permit the relay spring to act.

Normally, the switches 157, 164, 175', and 197 are open while the switches 163 and 154 are closed, and the switch 165 is in the position 15 shown, connecting the conductors 176 and 177. In each instance, as noted above, the switch may be operated against the action of a spring tending to keep it in its normal position.

Closing of the switch 137 simultaneously with 20 the switch 136 energizes slow release relay No. 1 to close switch 157, closing of which in turn will energize slow release relay No. 2 to close the switch 164, to open switch 163, and to operate the switch 165 to disconnect conductors 176 and 177 and to connect conductors 177 and 192. Closing of the switch 164 will energize the vibrating 25 reed relay, whereas the described operation of the switch 165 will deenergize slow release relay No. 4, thus closing switch 175' through its 30 spring and operating rotary switch No. 2 by current now available through switch 165.

Energizing of the vibrating reed relay will in turn energize slow release relay No. 3 which will open the switch 154 and thus break the circuit 35 through the homing contacts 149 and wiping contact 146, in the circuit of which the switch 154 is located, as previously described.

The two rotary switches Nos. 1 and 2 will operate simultaneously under the action of the first 40 impulse received, but the action of the slow release relay No. 4 holds the wipers 181 and 184 on the first contact 182 and 186, respectively, while the rotary switch continues to step the wiping contacts 146, 147, and 148.

These wiping contacts 146, 147, and 148 will 45 continue to step around until the thread breaks and will move one step or one contact 149, 150, and 151, respectively, for each impulse received by the quick-acting relay. While this movement of the wiping contacts is taking place, all of the slow-release relays No. 1, No. 2, No. 3, No. 4, and the vibrating reed relay will have remained 50 energized, because of their slow-release feature, and thus prevent further movement of the rotary 55 switch No. 2.

For the sake of example, assume that ten impulses have been transmitted to rotary switch No. 1. Then it will be seen that the three wiping contacts 146, 147, and 148 have moved to 60 their positions shown in dotted lines. In this connection, these wiping contacts are shown at zero positions in full lines, and it will be noted that in those positions each of the wiping contacts is in a dead or idle position. It will also be noted that when contact 146 engages with any one of the contacts 149 except the "zero" one, a 65 circuit will be closed at that point.

It will also be noted that the wiping contact 184 is in engagement with a blank contact 186 70 as the result of the first impulse.

Rotary switch No. 1 acts as a selector switch to select and partially close a circuit through one or more of the solenoids 92. For example, with the number 10 to be recorded, as is assumed 75

to be the case, then the selector switch has selected and partially closed circuits through the solenoids 92-1 and 92-0. The wiping contact 147 will have moved to the position shown in dotted lines, where it rests upon the tenth contact 150. Similarly, the wiping contact 148 has moved a corresponding amount and over a corresponding number of contacts 151, but these contacts are all dead or blank except the tenth one, which is connected to solenoid 92-0.

The nine contacts 150 following that marked 10 are all connected to the solenoid 92-1, so that for any figure between 10 and 20 this solenoid is selected by the wiping contact 147. At 15 the same time it will be seen that the wiping contact 148, after passing the contact 151 indicated by the numeral 10, will select one of the solenoids 92-1a and 92-2, etc. Similarly, when the wiping contact 147 is engaging any one 20 of the contacts 150 between the points marked 20 and 30, the wiping contact 148 will engage one of the contacts 151 between the points marked 20 and 30 so as to energize one of the solenoids 92-1a, 92-2a, 92-3, etc.

25 From the above it will be seen that for every number from 1 to 9, inclusive, it is possible to complete a circuit through one of the solenoids 92-1 to 92-9, inclusive, whereas for every number from 10 to 32, inclusive, two circuits may be completed through two different solenoids corresponding to the two digits in the number.

30 Rotary switch No. 2 may be termed the energizing switch, and completes the circuits through the solenoids selected by the selector switch, and 35 which circuits have been partially completed by the selector switch. The complete circuit through one of the solenoids leads from one side of the rectifier 129 through the conductors 144, 143, 183, the contacts 184 and 186, the selected solenoid, 40 one of the contacts 150 or 151 and thence to the wiping contact 147 or 148, as the case may be, to the conductor 195, switch 163, conductor 196, switch 197, conductors 198, 156, and 138. In the diagram, the principal part of this circuit is 45 shown in heavy lines.

Now take the time when the wiping contacts 147 and 148 have come to rest so that the circuits through the various solenoids 92 have been selected, and the wiping contact 184 has moved one 50 contact from the position indicated.

Slow release relay No. 1 will remain energized as long as impulses keep reaching it, but when those impulses cease, which occurs when the thread breaks, then this relay will cease to be energized and the switch 157 will open, thus in 55 turn causing the deenergizing of slow release relay No. 2 and the vibrating reed relay.

Slow release relay No. 2, in dropping out, energizes slow release relay No. 4, causing the wiping 60 contacts 181 and 184 to move in a clockwise direction around over the contacts 182 and 186, respectively, back to their normal position which is indicated in the diagram. In its movement, the wiping contact 184 will complete the circuits 65 through the various solenoids 92 which have been selected by the selector switch. The movement of the wiping contact 184, however, is slowed up by slow release relay No. 4.

The switches operated by the magnets 175 and 70 180, respectively, will alternately energize and deenergize these two magnets so as thus to delay the action of rotary switch No. 2 or the energizing switch and thus insuring that the wiping contact 184 will have sufficiently long engagement 75 with any of the contacts 185 which are in the se-

lected circuits so that the solenoids 92 in those same circuits may be properly energized.

The vibrating reed relay will maintain slow-release relay No. 3 energized until the above described action has taken place, so as to maintain the switch 197 closed and the switch 154 open. When the vibrating reed of the vibrating reed relay comes to a central position, then the slow release relay No. 3 is deenergized and the switch 197 opens and the switch 154 closes.

Opening of the switch 197 breaks the circuit of the selector switch, and closing of the switch 154 puts current on the contacts 149 and completes the circuit through the magnet 141, thus causing the wiping contact 146 to rotate step by 15 step in a clockwise direction until it reaches the position shown in full lines in the diagram, which movement is generally termed "going home." This action will be more fully explained later. During this movement, of course, the wiping contacts 147 and 148 move with the wiping contact 146 until they too reach the full line positions indicated.

It will be noted that the numbered contacts 186, which are connected to the various solenoid 25 circuits and therefore are "live", are spaced apart a substantial distance on the arc of contacts so as to insure that the contact 184 only closes one circuit at a time. It will also be seen that it is impossible for the wiping contact 184 to close two 30 circuits to operate the same recording key.

For example, the recording key numbered 1 may be operated by either one of the two solenoids 92-1 or 92-1a, and it will be seen that the contacts 186 connected in the circuits of these two 35 solenoids and numbered 1 and 1a respectively, are spaced apart widely on the arc of contacts 186. Thus if, for example, the recording key numbered 1 is to be actuated twice in succession to record the numeral 11, it will have time to operate once under the action of the solenoid 92-1 when energized by closing of its circuit at contacts 186-1, and then return to inoperative position before it is acted upon under the influence of the solenoid 92-1a, when energized by closing 45 its circuit at contact 186-1a.

Now assuming that the thread has broken after a force of ten ounces has been applied to it, the breakage will not affect the operation of the motor which will continue to rotate the cam 41. The 50 ratchet 68 will hold the pointer 66 in the position at which it was when the thread broke until released by the later action of the solenoid 70.

The wiping contact 184 will have moved over all of the contacts 186, as previously described, including the contacts 186-1 and 186-0, thus successively energizing the solenoids 92-1 and 92-0, to record the number 10 on the recorder.

The solenoid 92-M should be energized to print each recording, and for that purpose the 60 circuit through that solenoid is closed by engagement of the wiping contact 184 with the contact 186-M, which is located so that the contact 184 may engage therewith only after having passed over all of the other live contacts. Energizing of 65 the solenoid 92-M will cause one of the fingers 87 to operate the key 80, which will cause printing of the recorded figures upon the strip 83 and movement of the strip into position to present a blank space for printing of the next set of figures. This movement of the strip is effected by standard mechanism incorporated in the adding machine, as is well known.

The wiping contact 184, in passing over the contact 186-M, which is connected to the con- 75

ductor 201, thus energizes rotary switch No. 3 momentarily and causes the wiping contacts 187 and 188 to move one step or one contact 190 and 191, respectively.

It will be seen that only every fifth contact 191 is connected to one of the conductors 206 so that every break of the thread causes the movement of the wiping contact 188 from one contact 191 to the next adjoining one, but engagement 10 of the wiping contact 188 with the contact 191 acts as a switch to help in closing a circuit, only at every fifth or numbered contact 191. This is the reason why the pointer of the switch 106 is shown at a figure corresponding to the number of 15 breaks desired, divided by five.

Movement of the wiping contact 187 over the homing contacts 190 will have no effect at this stage, but when the wiping contact 188 comes in contact with the contact 191—5, corresponding to 20 the setting of the switch 106 in the selected example, a circuit will be completed through the conductor 205, contacts 188, 191—5, one of the conductors 206, the switch 106, conductor 208, and trip relay 111, which will open the switch 110 25 and stop the operation of the motor.

Before another set of tests takes place, the reset switch 105 should be operated manually to close the circuit through the homing contacts and thus cause rotary switch No. 2 to return the contact 187 to initial position.

After each break of the thread, until the motor is stopped, the cam shaft 35 continues its operation, causing successive breaks in successive lengths of thread fed into position to be broken. 35 During the rotation of the cam shaft, the switches 95 and 96 are periodically opened and closed. Closing of the switch 96 takes place after the thread is broken, and will operate the ratchet solenoid and cause the ratchet 68 to release the pawl 67 to permit the pointer 66 to return to zero 40 position before tension is placed upon another length of thread. This return is caused by the usual mechanism of the scale, which is of standard construction and need not be described or illustrated in detail.

When the operation of the motor is discontinued upon completion of the required number of test breaks, the quantities recorded on the paper of the calculating machine or recorder may be totalized in the usual manner common with 50 such machines. The result then will be a printed or typed record on a paper strip which has been made automatically.

Referring now to Figs. 13, 14, and 15, I have indicated therein a different embodiment of a 55 certain part of the invention, more particularly the part relating to the sending of the impulses which actuate the recording mechanism.

I have found that for some types of testing apparatus where the units to be measured and recorded are relatively small, or where for any other reason the holes 11 in the shutter 76 are placed close together, and then a vibration occurs which will disturb the relation of the shutter to the lamp and cell, such vibration may cause the shutter to flutter enough to send impulses, by changing the quantity of light reaching the cell. The structure and arrangement shown in Figs. 13, 14, and 15 are designed to obviate this 70 difficulty.

The parts appearing in Figs. 13, 14, and 15 which are identical with the parts already described have been given the same numerals, and a description of their function will not be repeated. For purpose of convenience, in Fig. 13

I have shown a certain duplication of parts, the shutter 76 and associated parts being shown twice, once on a large scale and once on a smaller scale which better fits into the wiring diagram.

Instead of the shutter 76 having a hole 11 for each ounce or other unit of force, I provide it in this embodiment with one hole for each two ounces, thereby cutting down the number of holes by half. Cooperating with the shutter, I provide two lamps 14a and 14b, connected in parallel, and 10 these lamps are so spaced apart lengthwise of the shutter that when one lamp is shining through one of the holes 11, the other lamp has its beam of light directed against an opaque part of the shutter between two of the holes. In this instance, the center to center spacing of the lamps is $\frac{3}{2}$ the center to center spacing of the holes.

Cooperating with each of the lamps is a photoelectric cell 13a, 13b, respectively. By means that will be explained later, when the scale pointer 66 20 indicates zero, neither lamp 14a nor 14b will be lighted, nor in registry with one of the holes, but the end hole 11—1 is disposed between the beam of light from the two lamps, as plainly shown in Fig. 13.

Now as the pointer 66 moves from zero to 1 on the scale face 66', the light in both lamps is lighted, by means to be described later, and the next to the last hole 11—2 will come into registry with the beam of light from the lamp 14b, as 30 shown in Fig. 14, and cause this beam to act upon the cell 13b. However, the end hole 11—1 will not have reached a position to register with the beam of light from the lamp 14a, as shown in Fig. 14.

Then, as the pointer moves to 2 upon the scale face, the end hole 11—1 will be brought to a position to register with the beam of light from the lamp 14a and the next hole 11—2 will pass out of registry with the beam from the lamp 14b, 40 all as shown in Fig. 15. This operation will be repeated, first one hole coming into registry with one beam of light and then the other hole coming into registry with the other beam of light, either one lamp or the other acting upon its cell 45 for each unit of measurement.

Each cell is placed in the input circuit 124a—125a or 124b—125b of an amplifier 122a or 122b, respectively. These amplifiers are connected in parallel to the conductors 121 and 123, and they 50 act in the same manner as the amplifier 122, which in the other embodiment is connected to the same conductors.

In the embodiment being described, instead of the switch 99 being used as shown in Fig. 3, I use 55 a double switch indicated generally by the numeral 99' in Fig. 13, and controlled by the position of the bracket 6. This switch comprises four spring contacts in what is known as break-make assembly, these contacts being identified as 209, 60 210, 211, and 212. When the pointer 66 is at zero, the various contacts have the relation shown in Fig. 13, namely, the two contacts 209 and 210 are out of engagement with each other, and the contacts 211 and 212 are in engagement with each other, in which position they are held by the bracket, as shown.

Now as the bracket 6 is moved downwardly under the tension of the thread before it breaks, the contact 212 will move out of engagement with 70 the contact 211, and the contact 209 is brought into engagement with the contact 210, the contacts 209 and 212 moving together under their spring actions and through the arrangement of insulating spacers 213.

- Therefore, as soon as tension on the thread is sufficient to move the bracket 6 downwardly, the result is to open one circuit and close another. The circuit controlled by the contacts 211-212 is a shorting circuit and includes a contact 215 centrally disposed on an armature 216 adapted to be operated by either one of the magnets 217 or 218 connected respectively in the output circuits of the amplifiers 122b and 122a.
- 10 This contact 215 is between and may contact with either one of two spring contacts 219 or 220, both connected to a conductor 221 which leads back to the contact 212. The conductor 214 is in turn connected through a battery 222 to the conductor 133, and the conductor 221 is connected directly to the conductor 134.
- 15 These conductors 133 and 134 are connected to opposite sides of the magnet 135 controlling switches 136' and 137'. These switches operate in much the same manner as the switches 136 and 137, except that in the present embodiment the magnet 135 is normally energized, whereas in the first described embodiment it is normally de-energized. The reason for this will be more fully described later.
- 20 Connected to the circuits of one of the cells, here shown as the cell 73a, are conductors 223 and 224 containing two high resistance units 225 and 226, and the circuit through these resistances comprises a switch 227 which is adapted to be closed by the shutter or pointer when at zero position, as indicated in Fig. 13.
- 25 Assuming that the pointer is at zero, then the circuit through the lamps is broken between the contacts 209 and 210, while the contacts 211 and 212, and 215 and 219, are in engagement, respectively. The various holes in the shutter occupy the positions shown in Fig. 13 and the magnets 217 and 218 are deenergized.
- 30 40 As soon as the pointer and shutter have moved a distance corresponding to one unit of measurement, then the next to the last hole 77-2 will come into registry with the lamp 74b as previously described, and as shown in Fig. 14, and will thus affect the cell 73b, energizing the magnet 217 and attracting the armature 216 to that magnet and away from the magnet 218. This will break the circuit between the contacts 215 and 219 and after a very short interval of time will make a circuit between the contacts 215 and 220. This action will momentarily deenergize the magnet 135 by breaking the circuit through the battery 222 and the magnet, thus permitting the switches 136' and 137' to close. When, however, the contact 215 engages the contact 220, the circuit is again completed through the magnet 135 and the battery 222, again opening the switches 136' and 137'. The result is the sending of an impulse to the magnet 135, which causes it to act in the same manner as described above in the first described embodiment, and then the immediate breaking of the circuit of that magnet, so that no further impulses may be sent no matter how much the shutter may vibrate.
- 45 50 55 60 65 70 75 The two magnets 217 and 218 are so constructed that the armature will stay in position against the core of the magnet last energized. Now assuming that the shutter and pointer move a distance corresponding to another unit of weight, the last hole 77-1 will come in registry with the lamp 74a and cell 73a, as shown in Fig. 15, and thus energize the magnet 218, which will cause an impulse to be sent to the magnet 135 in the same manner as just described above.
- These operations will be repeated as each hole

comes into registry with one of the lamps and its corresponding cell until the thread breaks, and the registry of a hole with a lamp results in only one impulse.

When the thread breaks, the bracket 6 will rise to the position shown in Fig. 15, opening the lamp circuit by moving the contact 209 out of engagement with the contact 210 and closing the shorting circuit by engagement of the contacts 211 and 212.

10 While the pointer and shutter are returning to zero, the lamps will thus be extinguished and no light will reach the cells from the lamps and thus no impulses will be sent. As the shutter and pointer reach zero, the switch 227 will be closed, 15 short circuiting the input to the amplifier 122a, causing an impulse of current to flow through the magnet 218 in the same manner as if light reached the cell 73a, and thus causing the armature 216 to return to the position indicated, if not already 20 there. If already there, the short circuiting has no effect.

The above operation is used in order to insure that the armature 216 shall always be at the indicated position when the pointer is at zero.

25 Assuming that the armature 216 is moved from engagement with the core of the magnet 217 to engage with the core of the magnet 218, or, in other words, to the position indicated, as just described, then that act would cause an impulse 30 to be sent to the magnet 135 unless some means were provided to prevent it. Such means is provided by the shorting circuit comprising the conductor 214, contacts 211 and 212, and conductor 221, thus providing a short circuit between the 35 conductors 214 and 221 and avoiding the sending of any impulse to the magnet 135 through the battery 222.

40 Referring now to Figs. 7 and 8, I have shown therein a type of rotary switch which may be 45 employed in connection with the various circuits described above. Assume that the switch illustrated in these two figures is rotary switch No. 1 mounted upon the shaft 145. The stationary contacts are arranged in banks, the contacts 149 being arranged in two banks, the contacts 150 in two other banks, and the contacts 151 in two other banks. In order to avoid the necessity of an unusually large switch, each bank consists of only twenty-five contacts, and therefore the contacts are arranged in two separate banks, and instead of one wiping contact 146, I have indicated two such contacts. Similarly, instead of one wiping contact 147 and 148, respectively, I have shown two such contacts. This expedient is well known in the art.

45 50 55 60 65 70 75 The wiping contacts 146, 147, and 148 are all secured to the shaft 145 but insulated from each other. Intermittent rotation of the shaft with the wiping contact thereon is obtained by means of the magnet 141 having an armature 263 pivoted at 264 upon a frame 265, and having an upwardly extending arm 266 provided at its upper end with a pivoted pawl 267 engaging a ratchet 268 secured to the shaft 145 and held against counterclockwise movement, as view in Fig. 7, by means of a spring 269. The armature is held in normal position by means of a spring 270.

In operation, as an impulse energizes the magnet 141, it will be seen that the arm 266 of the 70 armature is moved towards the right of Fig. 7, and then as the effect of the impulse stops and the magnet is deenergized, the spring 270 will cause the pawl 267 to actuate the ratchet one step.

Upon each movement of the arm 266 towards 75

the right of Fig. 7, a button 271 carried thereby will open the homing contacts 272 and 273 by engagement with the contact 273. These contacts will be closed upon the spring causing the 5 actuation of the pawl and ratchet as described above.

The homing switch 152 comprising the contacts 272 and 273 is in a circuit, as shown in Fig. 4-B, which includes the wiping contact 146 and 10 the homing contacts 149 and also the magnet 141. When slow release relay No. 3 permits the closing of this circuit, then the operation of the pawl and ratchet will be repeated indefinitely until the wiping contact 146 engages one of the bank contacts 15 149 which is not energized. As plainly indicated in Fig. 4-B, the zero contact 149 is a blank so that when the wiping contact 146 engages that blank contact, the rotation of the switch will cease.

20 The general construction of the type of rotary switch described above is known in the art, as is also the necessary construction of relays to make them operate relatively slowly. It has not been thought necessary to describe any particular 25 construction of slow-acting relay, nor for that matter of a vibrating reed relay, since that type of relay is also well known in the electrical art.

In Figs. 5 and 6 I have shown a circuit which 30 may be used in place of the circuit shown in Figs. 4A and 4B. Generally speaking, this circuit will perform the same functions as the circuit previously described, and will also perform certain other functions which will be brought out during the following description. The same numerals 35 have been applied to corresponding parts in the two circuits, so far as possible.

The "rotary switch No. 1" is similar in both circuits, although different in details. This switch is shown very diagrammatically in Fig. 5 but on 40 a larger scale in Fig. 6. In Fig. 5, no attempt has been made to show the details of "rotary switch No. 1", nor the details of the connections leading therefrom. In Fig. 5, it has merely been indicated that those connections lead to the adding machine, and the solenoids 92 of the adding machine are indicated in Fig. 6, in the same general manner as in Fig. 4B.

The shutter 16 in Fig. 5 is shown in connection with two lamps and associated photo-electric cells, as in Fig. 13.

50 Current is supplied from the main 274 which supplies current to the rectifier 129 through a switch 275 controlling the power relay 276. Similarly, a switch 277 connected to any suitable 55 source of power may be used to control relays 278 and 278' which control the passage of current to the motor 37.

The circuit of Fig. 5 also includes rotary switch No. 3, corresponding to the similarly identified 60 switch of the other embodiment, and also a "breaks required" switch 106, serving the same function as before.

The lamps are controlled by a double throw switch 99' operating a shorting relay 135 as before. The rotary switch No. 2 and the relays between that switch and rotary switch No. 1 of the old circuit are replaced by relays indicated by the legends R-5 to R-12, inclusive.

By the numerals 279 and 280 are identified 70 cables or collections of wires forming conductors, in this instance each of the lines so identified on the drawings indicating seven wires. Similarly, the ten wires leading from the switch 106 to the switch R. S. No. 3 are shown as contained in a 75 cable 281.

The action of the shutter will cause impulses to pass through certain of the wires in cables 279 and 280 to the amplifiers numbered 1 and 2, respectively, amplifier No. 1 being indicated for odd numbers and amplifier No. 2 for even numbers. 5 The impulses sent to these amplifiers will cause them to alternately energize the two coils of a pole relay 282. The middle contact of the switch operated by this relay alternately closes and opens circuits to the two relays 283 and 284, each 10 of which has the characteristic of being slow to operate and which send impulses to the slow-acting relay 285 and to the quick-acting relay 286, these two relays being energized together.

Quick-acting relay 286 energizes the relay of 15 rotary switch No. 1 to step the contact of that switch around one point for each impulse. The slow-acting relay 285, on the other hand, stays closed until the impulses caused by the quick-acting relay cease and then it opens. Upon closing at the beginning of the chain of impulses, the slow-acting relay in turn closes relays R-5 to R-12, inclusive, in succession and, on the other hand, when it opens, these relays R-5 to R-12, 20 inclusive, drop out one after the other.

When relay R-8 drops out, the result is to 25 apply voltage on the pointer contact 147, thus causing the printing of the first figure of ten or any number above ten. Then when relay R-9 drops out, voltage is placed on the pointer contact 148, causing the printing of any number less than ten or the second digit of any number over ten. Thus it will be seen that the switches of the relays R-8 and R-9, respectively, perform the same function as the energizing switch 30 identified as "rotary switch No. 2" in Fig. 4-B. When relay R-12 drops out, voltage is applied 35 to the solenoid 92-M.

The same relay is used to control a magnetic 40 counter operated by a magnet 287 (Fig. 6). This counter is of any known construction, the details of which are not necessary to an understanding of the invention claimed herein. It is used to count the number of breaks of thread which take place.

45 Just before the relay R-12 drops out, it energizes relays R-13 and R-14 simultaneously. However, these relays are so wound that R-13 operates first, cutting out R-14 and locking it in its inoperative position while R-13 is in operation. Nothing happens, however, until the next 50 break of thread takes place, at which time relay R-13 becomes deenergized, allowing R-14 to operate and sending one impulse to the rotary switch No. 3. This operation makes it possible 55 to have a larger number of breaks for the same number of contacts.

It sometimes happens that the length of thread being broken has an unusual weakness therein so that it is broken by a force which is too small 60 to cause even one impulse to reach rotary switch No. 1, in which case no record of the weak break would appear on the strip on the adding machine or recorder. To overcome this defect, a weak break control is used. This control may comprise 65 a mercury switch 288 (Figs. 5 and 11), the operation of which is controlled by a finger 289 which normally rests against the thread 2 on one side thereof, when the thread is continuous. As shown in Fig. 1, the finger is placed between the 70 two clamps 5 and 14 and moves in a slot 290 in the panel 10. The mercury switch is controlled by a solenoid 291.

The switch 288 may have either one of three 75 positions indicated in Fig. 11. The uppermost

position of that figure is the one which the switch takes when the thread is unbroken, and it will be seen that the switch is then open. Then as the thread is broken while being tested, the finger 289 will pass to the other side of the thread by a downward movement of the mercury switch. During this movement, the switch will be momentarily closed, such a condition being indicated at the middle position of the switch in Fig. 11, and then the switch will be opened again, as indicated in the bottom position in Fig. 11. After the thread is broken and before a new length of thread is fed into position to be broken, the solenoid 291 is actuated to pull the switch 288 back 10 to its uppermost position in Fig. 11.

When the finger passes the thread position as the thread breaks, one of two things may happen. If the breaking force is so small that no impulse has been transmitted to rotary switch No. 1, then 15 the circuit is closed through relays R-22 and R-23, which in turn operate relay R-24 and which in turn will energize the relay 278' to open the motor circuit. However, if the force needed to break the thread has been great enough to 20 cause one or more impulses to reach rotary switch No. 1, then R-12 will have been operated as described above, this opening the circuit to relay R-22 and R-23 so that they cannot be 25 energized to set in motion the chain of operations described above to stop the motor.

When a break is caused by a force too small to send even one impulse, such break is usually referred to as a "weak break", and consequently that expression will be used herein. When a 30 weak break takes place as described above, the motor is stopped and consequently the operation of the apparatus ceases until the motor is again started by the operator. This makes it possible to take proper account of the weak break in 35 determining the results of the tests. The motor may now be started again by operating the weak break restart button 292, which will open the circuit through the relay 278' and thus permit the switch controlled thereby to close the circuit to 40 the motor.

After the finger 289 has passed to the right of the thread as viewed in Fig. 11, it must be moved back to the other side of the thread position, and this is done by means of the solenoid 291. As it returns to initial position, the switch 288 is 45 momentarily closed in the same manner as it is closed momentarily when the thread breaks, but this closing on the return motion is rendered ineffective by the following means:

When the ratchet solenoid 70 is energized to release the ratchet from engagement with the pawl, there is also energized a relay R-26 which will open a switch in the same line as the switch 288, and thus when the solenoid 291 is subsequently energized to move the switch 288 back to 50 initial position, its temporary closing will not be effective, because its circuit is already open at another point.

When the thread is first fed between the clamps 5 and 14 and engaged thereby, it is preferable to hold the weak break finger 289 out of engagement with the thread for a second or two and then release it and return it again to the thread. In other words, when the thread is first engaged by the clamps, this will make a little slack in it, and until this slack is taken up by stretching the thread it is best to keep the finger out of engagement with the thread. This result is accomplished by the dash pot relay 293, the switch of which is in the circuit controlling 55

the solenoid 291. When this relay 293 is not energized, its switch is closed so that current may pass therethrough to the solenoid 291. When the relay 293 is energized, however, the dash pot associated therewith will prevent separation of the contacts of the relay switch for a period of seconds, depending upon the dash pot adjustment. When, however, the dash pot permits opening of the switch of relay 293, then the solenoid 291 is deenergized and the finger 289 10 may contact with the thread.

Looked at in another way, the finger 289 when returned to its initial position by the solenoid 291 is out of contact with the thread, being held by the solenoid a sufficient distance away from the 15 normal thread position for that purpose and so is not responsive to the tension of the thread. Then the solenoid 291 is deenergized and the finger 289 and switch 288 are governed entirely by the tension of the thread until the thread 20 breaks. The tension device 3 is preferably controlled by a release member which may be operated by a solenoid 294. The details of this release member are more fully described and claimed in my copending application Ser. No. 25 100,433, filed September 12, 1936, and will not be further described.

The magnets 63 which are used to control the clamps 5 and 14, respectively, are preferably energized in the manner more fully described and 30 claimed in my said copending application Ser. No. 100,433, in such a way as to avoid damage to the thread engaged by the clamps. This is done by energizing the magnets first with a voltage that will cause the jaws of the clamp to engage 35 the thread lightly and then with a higher voltage that will cause a firmer engagement of the thread by the jaws. This is done by means of two switches 295 and 296 (Figs. 5, 9, and 10) operated by cams 297 and 298 on the shaft 35 (Fig. 2). 40 The extreme positions of these two switches are shown in Figs. 9 and 10, and their operation is more fully described in said copending application Ser. No. 100,433. In addition to operating the clamp magnets as described in said copending application, the switch 295 is connected to a 45 conductor 299 which leads to the ratchet solenoid 70 and the other parts, as plainly shown in Fig. 5, whereby this single switch may be used to control several instrumentalities. The two 50 switches are mounted upon two pivoted blocks which are tipped by the action of the cams, as shown in Figs. 9 and 10 and more fully described in said copending application.

Referring now particularly to Fig. 6, it will be 55 seen that the contacts controlling the solenoids 92 are arranged somewhat differently than in the other circuit shown in Fig. 4-B. The pointer contacts 147 and 148 will move together. The first nine contacts 147' engaged by the contacts 60 147 are blanks, it being remembered that when these blank contacts are engaged by the contacts 147, the contact 148 is engaging live contacts numbered 1 to 9, inclusive, and operating correspondingly numbered solenoids 92. The tenth contact 147' engaged by the contact 147 65 is alive, since it is connected to the solenoid 92-1. This first live contact 147' is one of a group of ten, all of which are connected to the same solenoid 92-1, so that as the pointer contact 148 passes over the second group of ten contacts 148', the solenoid 92-1 will remain energized. Similarly, it will be seen that there 70 are successive groups of contacts 148', the contacts in each group being numbered successively 75

1 to 9 inclusive, and 0, and for each one of these groups beyond the first group there is a corresponding group of contacts 147 adapted to be engaged by the contact 147 and thus cause energizing of the appropriate magnet to cause printing of the first digit.

While I have shown the invention as embodied in specific forms, it is to be understood that various changes in details may be made without departing from the scope of the invention, as defined by the appended claims.

I claim:

1. In combination, a plurality of electrical circuits to be energized, a selector switch adapted to close any one of said circuits at one point therein, each of said circuits having a normally open switch therein at a point other than at said selector switch, means to close said second-named switch for the circuit closed by said selector switch, after a time interval, said selector switch being operable by electrical impulses, a force applying device adapted to cause the sending of said impulses, and means rendering said device inoperative when the force applied thereby is too weak to cause the sending of an impulse.
2. In combination, a plurality of electrical circuits to be energized, a selector switch adapted to close any one of said circuits at one point therein, each of said circuits having a normally open switch therein at a point other than at

said selector switch, means to close said second-named switch for the circuit closed by said selector switch, after a time interval, said selector switch being operable by electrical impulses, a force applying device adapted to cause the sending of said impulses, and means rendering said device inoperative when the force applied thereby is too weak to cause the sending of an impulse, 5 said means comprising an electric circuit and a switch therein closed by said weak force. 10

3. In combination, a plurality of electrical circuits to be energized, a selector switch adapted to close any one of said circuits at one point therein, each of said circuits having a normally open switch therein at a point other than at 15 said selector switch, means to close said second-named switch for the circuit closed by said selector switch, after a time interval, said selector switch being operable by electrical impulses, a force applying device adapted to cause the sending of said impulses, means rendering said device inoperative when the force applied thereby is too weak to cause the sending of an impulse, 20 said means comprising an electric circuit and a switch therein closed by said weak force, and 25 means preventing closing of said last-named switch when the force applied by said device is sufficient to cause the sending of an impulse.

THOMAS J. NUNAN. 30
